UNITED STATES PATENT OFFICE.

ROY F. McINTIRE, OF PELLA, IOWA.

DRAFTING INSTRUMENT.

1,225,464.

Specification of Letters Patent.

Patented May 8, 1917.

Application filed May 10, 1916. Serial No. 96,650.

To all whom it may concern:

Be it known that I, Roy F. McINTIRE, a citizen of the United States, residing at Pella, in the county of Marion and State 5 of Iowa, have invented new and useful Improvements in Drafting Instruments, of which the following is a specification.

This invention relates to a drafting instrument and has for its primary object 10 to form a single object capable of presenting a number of angles.

Another object of the invention is to provide a device having a number of flat faces, the corners formed at the juncture 15 of the faces being arranged at various angles to each other.

Another object of the invention is the manner of forming these faces so that a good purchase can be had between the 20 device and the fingers of the user.

With these and other objects in view the invention consists in the construction, combination and arrangement of parts as will be hereinafter more fully described, illustrated in the accompanying drawing and pointed out in the claim hereunto appended.

In the drawing:

Figure 1 is a perspective view of the device in its solid form,

Fig. 2 is a perspective view of the device when made hollow,

Fig. 3 is a sectional view on line 3—3 of Fig. 2,

Fig. 4 is a diagrammatic view of the 35 faces of my invention.

The block 1 may be cast solid as illustrated in Fig. 1 or formed in sections so as to be hollow as illustrated in Figs. 2 and 3. The block is formed with four faces indicated by the numerals 2, 3, 4, and 5. The face 2 which is in the form of a right angle triangle, the hypotenuse of which being arranged at a 45 degree angle. The face 3 is in the form of a right angle triangle with the hypotenuse arranged at a 60 degree angle and the same is true of the face indicated by the numeral 4. The face 5 has all of its edges arranged at an acute angle to each other. It is of course 50 to be understood that the hypotenuse of the face 3 and the hypotenuse of the face 4 will represent 60 degrees when in one

position whereas they will represent 30 degrees when in another position. In Fig. 2 of the drawing it will be seen that the 55 major portion of the face is depressed so as to form shoulders 6 arranged to be engaged by the user so as to readily lift the object or block of any surface. When considering the manufacture of the device I 60 wish it to be understood that I do not desire to be limited to the manner of making the device as illustrated in the drawing as three sides of the face may be stamped from a single sheet of material while the 65 fourth face may be secured to the first mentioned face in any suitable manner or the whole body of the device may be stamped from a single sheet of material and have the edges secured in any suitable manner. 70

From the foregoing description taken in connection with the accompanying drawing it should be apparent that I have provided a device which is admirably adapted for the purpose for which it is intended, that the 75 device is simple, durable and efficient of construction and that the device may be manufactured and sold at a comparatively low cost.

Changes in the form, proportion and 80 minor details of construction may be made within the scope of the claim without departing from the spirit or sacrificing any of the advantages of the invention.

What I claim is:

As a new article of manufacture, a drafting block having four flat faces, two faces being identical and each in form of a right angle triangle, the hypotenuse of each being disposed at angles of sixty and thirty 90 degrees to the sides thereof, and having another face in the form of a right angle triangle having its hypotenuse at an angle of forty five degrees to its sides, the remaining face being formed of a triangle 95 all the edges of which are being arranged at acute angles to each other.

In testimony whereof I affix my signature in presence of two witnesses.

ROY F. McINTIRE.
